DESIGN FOR A BOTTLE

Roger Bigar, New York, N. Y.

Application April 27, 1946, Serial No. 129,050

Term of patent 3½ years

(Cl. D58—9)

To all whom it may concern:

Be it known that I, Roger Bigar, a citizen of France, resident of New York city, in the county of New York and State of New York, have invented a new, original, and ornamental Design for a Bottle, of which the following is a specification, reference being had to the accompanying drawing, forming part thereof.

In the drawing:

Fig. 1 is a front elevational view of a bottle, showing my new design;

Fig. 2 is a side elevational view thereof;

Fig. 3 is a rear elevational view; and

Fig. 4 is a bottom plan view.

I claim:

The ornamental design for a bottle, substantially as shown.

ROGER BIGAR.
